GROUNDING SWITCH OPERATING
MECHANISM

Charles W. Smith, Sharon, Pa., assignor to Westinghouse Electric Corporation, East Pittsburgh, Pa., a corporation of Pennsylvania

Application October 20, 1949, Serial No. 122,400

10 Claims. (CL 74—528)

1

This invention relates to transformer grounding switches and particularly to the operating mechanism for actuating grounding switches.

In the operation of electrical apparatus such as transformers, it is desirable to disconnect the transformer from the power circuit and to ground the high voltage feeder when repairs or changes are to be made in order to protect the workman from injury in case someone should accidentally close the line breaker and again connect the transformer to the circuit. It is also desirable to provide for preventing the improper operation of the grounding switch such, for example, as moving it from the open position to the ground position when the transformer or feeder is energized, which operation might cause serious damage to the apparatus or persons.

Transformer grounding switches have been developed heretofore for accomplishing such operations, but such switches utilize operating mechanisms which consist of many complex mechanical parts which are subject to frequent replacement due to wear and breakage, a factor resulting in the loss of much time and money to the industry.

An object of the invention is to provide an operating mechanism for effecting a positive movement of a transformer grounding switch from an open position through a transformer position to the ground position.

Another object of the invention is to provide an operating mechanism for effecting a positive stop of a transformer grounding switch at the transformer position during movement of the switch from an open position to the ground position and to provide means associated with the operating mechanism to effect a positive lock of the transformer grounding switch when the switch is in any one of the open, transformer and ground positions.

A further object of the invention is to provide an operating mechanism for a transformer grounding switch which is of a very simple mechanical structure, permitting operation of the switch by an inexperienced operator and reducing the time and expense involved in repairing and replacing faulty parts.

Other objects of the invention will become apparent from the following description of an operative embodiment of the invention when taken in conjunction with the accompanying drawings, in which:

Figure 1 is a view in side elevation of the operating mechanism;

Fig. 2 is a view in front elevation of the op-

2

erating mechanism for the grounding switch illustrated as positioned in the open position;

Fig. 3 is a view similar to Fig. 2 illustrating the operating mechanism for the grounding switch at a position between the open and transformer positions of the switch during movement of the switch from the open position towards the ground position;

Fig. 4 is a view similar to Fig. 2 illustrating the operating mechanism for the grounding switch positioned at the transformer position;

Fig. 5 is a view similar to Fig. 2 illustrating the operating mechanism for the grounding switch at a position between the transformer and ground positions of the switch during movement of the switch from the open position towards the ground position;

Fig. 6 is a view similar to Fig. 2 illustrating the operating mechanisms for the grounding switch positioned at the ground position; and

Fig. 7 is an enlarged front view of a part of the operating mechanism of Figs. 1 through 6 illustrating the three relative positions assumed by a positive stop member during movement of the switch from the open position through the transformer position to the ground position.

Referring to the drawings and in particular to Figs. 1 and 2, there is illustrated a grounding switch operating mechanism 10 embodying the teachings of this invention. In this embodiment the mechanism 10 is provided with a channel support member 12 for mounting the mechanism on a suitable panelboard or the like (not shown), the channel member 12 having a shaft 14 extending outwardly therefrom at one end thereof disposed to be rotated relative thereto. In order to operate the grounding switch (not shown) through a number of switching positions such as open, transformer and ground positions, a lever 16 is disposed with one end thereof secured to the shaft 14, the other end being adapted to be secured to the grounding switch (not shown). The lever 16 is thus rotatable with the shaft 14 to progressively actuate the grounding switch (not shown) through predetermined positions as the shaft 14 is rotated.

In order to effect the rotation of the shaft 14 and consequently actuate the lever 16, an arm member 18 is provided having one of its ends secured to the shaft 14. The arm member 18 can therefore be rotated relative to the channel support member 12. As illustrated, the arm member 18 is provided with a shaft 20 adjacent the free end thereof and disposed for rotation therein. An operating handle 22 is provided on the shaft

26 to effect the rotation thereof and to move the arm member 18 to effect thereby a corresponding rotation of the shaft 14 to move the lever 16 through the various switch positions.

Mounted on the base of the support member 12 is an arcuate member 24 having disposed therein a pair of offset recesses or slots 26 and 28 having sides 30-32 and 34-36 respectively. The offset recesses or slots 26 and 28 are disposed longitudinally of the arcuate member 24 to cooperate with recess engaging means (referred to hereinafter) affixed to the end of the shaft 20 for effecting a control of movement upon the shaft 20 and consequently for effecting a corresponding control of movement upon the grounding switch (not shown) during movement of the grounding switch (not shown) from the open position through the transformer position to the ground position. The recess engaging means comprises a segmentally shaped element 38 having a flat side 40 and a curved side 42, the element 38 being disposed for predetermined movement along the slots 26 and 28 and to engage restraining means disposed in spaced relation along the recesses or slots 26 and 28 in predetermined positions to effect a positive stop of the element 38 in such positions. In this instance the restraining means along the offset slots 26 and 28 comprise a number of substantially circular enlargements 44, 46 and 48 of the recesses or slots 26 and 28, the enlargements being disposed in positions corresponding respectively to the ground, transformer and open positions of the grounding switch (not shown).

In order to prevent movement of the grounding switch (not shown) from the open position to the ground position directly, the enlargement 46 is disposed between the enlargements 44 and 48 for interconnecting the adjacent ends of the offset recesses or slots 26 and 28 to provide a tortuous path for movement of the element 38 between the open and ground positions. The enlargement 46 comprises an arcuate extension 50 of one terminal of the recess side 30 and an arcuate extension 52 of one terminal of the recess side 36. As viewed in Figs. 2 through 7 the extensions 50 and 52 are disposed in diametrically opposite relation and have the configurations of minor arcs of a circle (not shown), the extensions 50 and 52 being disposed for joining together the recess sides 30, 34 and 32, 36 respectively, to provide the tortuous path for movement of the element 38 between the open and ground positions.

The enlargement 44 is disposed for receiving the element 38 therein for effecting a corresponding positioning of the grounding switch (not shown) in the ground position, and comprises an arcuate extension 54 of the other terminal of the recess side 30. The extension 54 is disposed for joining together the recess sides 30 and 32 of the recess 26 and has the configuration of a major arc of a circle (not shown), the center of the circle (not shown) being offset in a direction toward the recess side 32 in relation to an arc line (not shown) disposed midway between the recess sides 30 and 32 and having a curvature identical to the curvature of the recess sides 30 and 32.

The enlargement 48 is disposed for receiving the element 38 therein for effecting a corresponding positioning of the grounding switch (not shown) in the open position, and comprises an arcuate extension 56 of the other terminal of the recess side 36. The extension 56 is disposed

for joining together the sides 34 and 36 of the recess 28 and has the configuration of a major arc of a circle (not shown), the center of the circle (not shown) being offset in a direction toward the recess side 34 in relation to an arc line (not shown) disposed midway between the recess sides 34 and 36 and having a curvature identical to the curvature of the recess sides 34 and 36.

10 Referring to Fig. 1, a locking mechanism 58 is illustrated as disposed for operation to effect a positive lock of the operating mechanism for the grounding switch (not shown) in any one of the open, transformer and ground positions. The mechanism 58 comprises a circular locking plate 60 carried by the shaft 20 adjacent the arm member 18 and disposed for rotation with the shaft 20 relative to the arm member 18. The locking plate 60 is secured to the shaft 20 as by a friction fit or may be keyed thereto, the shaft 20 extending through an aperture 62 therein which is disposed in offset relation to the center of the locking plate 60. In order to provide a positive lock for the operating mechanism when the mechanism is in any one of the open, transformer or ground positions, a spring-biased detent 64 is carried by the locking plate 60 adjacent the outer edge thereof at a point diametrically opposite the aperture 62 in the locking plate 60 for cooperating with an aperture 66 adjacent the end of the arm 18 as described hereinafter.

15 The detent 64 comprises a shaft 68 extending through an aperture 70 in the locking plate 60, the shaft 68 having affixed to one end thereof a knob 72 disposed to be manually actuated to move a ball-like protuberance or end 74 of the shaft 68 at the other end thereof, out of engagement with the aperture 66 in the arm member 18 when the operating mechanism is to be actuated from any one of the open, transformer and ground positions. In order to bias the end 74 into engagement with the aperture 66, a compression spring 76 is disposed about the shaft 68 between the end 74 thereof and the plate 60. 20 Thus, when the operating mechanism is in any one of the open, transformer or ground positions, it may be locked by rotating the handle 22 to rotate the plate 60 to a position where the end 74 of the detent 64 is biased into engagement with the aperture 66. On the other hand, the operating mechanism may be unlocked by a simple lifting of the knob 72 to compress the spring 76 and move the end 74 out of engagement with the aperture 66.

25 The following description of operation of the grounding switch operating mechanism 10 when taken in conjunction with Figs. 2 through 7 and especially Fig. 7 will serve to illustrate how the desired positive stop of the grounding switch (not shown) is effected at the transformer position during movement of the grounding switch (not shown) from the open position to the ground position.

30 As shown in Fig. 2, the element 38 is positioned within the enlargement 48 for effecting the positioning and a positive stop of the grounding switch (not shown) in the open position. In order to initiate the movement of the grounding switch (not shown) toward the transformer position, it is necessary to release the locking mechanism 58 which operates to lock the operating mechanism in the open position. This is accomplished by moving the knob 72 outwardly from the plate 60 to compress the spring 76 and disengage the end 74 from the aperture 66 as de-

scribed hereinbefore. Upon the release of the locking mechanism 58, the shaft 20 is then actuated in a direction for effecting a 90° rotation of the element 38 in a counterclockwise direction to swing the flat side 40 of the element 38 into alignment with the recess side 34 thereby permitting movement of the element 38 along the recess or slot 28 away from the enlargement 48 as the arm 18 is moved for effecting a corresponding movement of the lever 16 and the grounding switch (not shown) toward the transformer position. It is apparent that an actuation of the shaft 20 in a direction to effect a 90° rotation of the element 38 in a clockwise direction would fail to permit movement of the element 38 along the recess or slot 28 since, upon effecting such clockwise rotation, the curved side 42 of the element 38 is positioned in the recessed region 78 of the recess side 34 formed by the extension 56 of the recess side 36 to thereby prevent movement of the element 38 away from the enlargement 48. This effectively prevents movement of the arm 18 and consequently prevents a corresponding movement of the grounding switch (not shown) toward the transformer position.

It can be seen that movement of the grounding switch (not shown) is thus prevented while the element 38 is so disposed for if a force is applied to the shaft 20 to tend to actuate the element 38 longitudinally of the recess or slot 28 to effect a corresponding movement of the grounding switch (not shown) toward the transformer position, a portion of the curved side 42 of the element 38 is in engagement with a part of the recessed region 78 thereby preventing movement of the element 38 away from the enlargement 48 to prevent a corresponding movement of the grounding switch (not shown) toward the transformer position.

With the element 38 rotated to a position where the flat side 40 thereof is in alignment with the side 34 of the recess 28 as described hereinbefore, a force is applied to the operating handle 22 to move the element 38 and consequently the arm 18 towards the transformer position as shown in Figs. 3 and 4. As illustrated, a positive stop is provided in the transformer position by reason of the enlargement 46 connecting the offset slots 26 and 28. As the element 38 is moved into engagement with the enlargement 46, the curved side 42 engages the extension 52 to prevent further continuous movement of the operating mechanism towards the grounding position. When the element 38 is moved into position in the enlargement 46 as described for effecting a corresponding movement of the grounding switch (not shown) into the transformer position, the element 38 is disposed as is illustrated in Figs. 4 and 7.

Further movement of the grounding switch (not shown) away from the transformer position in a direction toward the ground position may be effected only upon the performance of a predetermined operation by the switch operator, which operation is time consuming, thereby effecting the desired positive stop of the grounding switch (not shown) at the transformer position. The effect of the positive stop is to give the switch operator the opportunity of determining whether or not the transformer is energized, the grounding switch (not shown) being in the transformer position during the delay or positive stop. Such a positive stop also provides sufficient time delay to permit the operation of

electrical interlocks (not shown) which are usually associated with the grounding switch. If the operator discovers that the transformer is energized, he may have the breakers again thrown open, whereupon he may perform the predetermined operation for permitting movement of the grounding switch (not shown) into the ground position without fear of causing damage to the transformer or the switch.

- 10 In order to effect the further movement of the operating mechanism towards the ground position from the transformer position illustrated in Fig. 4, it is necessary to actuate the shaft 20 in a direction for effecting a 180° rotation of the element 38 in the clockwise direction for moving the curved side 42 of the element 38 out of engagement with the extension 52, thereby swinging the flat side 40 of the element 38 around into alignment with the recess side 32.
- 15 20 A subsequent actuation of the shaft 20, while the element 38 is so disposed, in a direction for actuating the element longitudinally of the recess or slot 26 as shown in Fig. 5, effects a movement of the operating mechanism and consequently a corresponding movement of the grounding switch (not shown) toward the ground position illustrated in Fig. 6.

- 25 The performance of the predetermined operation and the subsequent actuation of the shaft 20 having been completed, free movement of the grounding switch (not shown) is permitted toward the ground position. After the element 38 is moved into the enlargement 44 for effecting a corresponding movement of the grounding switch 30 (not shown) into the ground position, the switch operator must then actuate the shaft 20 by means of the operating handle 22 in a direction to effect a 90° rotation of the element 38 in a counter-clockwise direction for operating the locking mechanism 58 to lock the operating mechanism and the grounding switch (not shown) in the ground position, thereby preventing accidental or unauthorized movement of the grounding switch (not shown) from the ground position.
- 35 40
- 45

The invention as described possesses several features of advantage over the grounding switches utilized in the industry today. The operating mechanism comprising the invention has relatively few mechanical parts and is, therefore, capable of prolonged service uninterrupted by breakdowns and failures of the operating parts, thereby resulting in a more efficient operation and less expenditure of time and money.

- 50 55 Improper operation of the operating mechanism is made impossible by the inclusion of the positive stop means for providing a positive stop of the grounding switch at the transformer position during movement of the switch from the open to the ground position. Movement of the switch directly from the open to the ground position is thereby prevented. The inclusion of the positive stop means thus prevents the switch operator from connecting the power circuit conductors to ground while energized, an operation which would result in the presence of a heavy grounding current and possible destruction of the switch. During the positive stop of the switch 60 at the transformer position, the operator may determine whether or not the transformer is energized and throw open the circuit breakers if the transformer is found to be energized and the electrical interlock (not shown) is operated. The switch may then be moved into the ground
- 65
- 70

position without fear of injury to the apparatus or the workmen.

A further feature of the invention which practically assures a safeguard against injury to the apparatus or the workmen is the locking mechanism associated with the operating mechanism of the grounding switch. The operation of the locking mechanism in any one of the various switch positions prevents the accidental or unauthorized movement of the switch operating mechanism from any one of the switch positions. It will be understood that a padlock or other suitable locking device may be utilized in lieu of the detent 64. Many modifications of the structure illustrated and described may be made within the spirit of the invention.

I claim as my invention:

1. In an operating mechanism for effecting the movement of a transformer grounding switch between an open position, a transformer position, and a ground position, in combination, a support member for the operating mechanism, a member having a longitudinal recess therein affixed to the support member, an arm member pivotally mounted on the support member, a shaft rotatably carried by the arm member, recess engaging means carried by the shaft disposed for movement longitudinally of the recess, a plurality of restraining means disposed in spaced relation along the recess to correspond to the open, transformer and ground positions of the switch, one of the restraining means cooperating with the recess engaging means for effecting a positive stop of the switch at the transformer position during a movement of the switch from the open position to the ground position, and means carried by the shaft disposed to cooperate with the arm member when the recess engaging means is in any one of the open, transformer and ground positions for locking the recess engaging means in such position.

2. In an operating mechanism for effecting the movement of a transformer grounding switch between an open position, a transformer position, and a ground position, in combination, a support member for the operating mechanism, a member having an arcuate longitudinal recess therein affixed to the support member, an arm member pivotally mounted on the support member, a shaft rotatably carried by the arm member, recess engaging means carried by the shaft disposed for movement longitudinally of the recess, and a plurality of restraining means disposed in spaced relation along the recess to correspond to the open, transformer and ground positions of the switch, one of the restraining means cooperating with the recess engaging means for effecting a positive stop of the switch at the transformer position during a movement of the switch from the open position to the ground position.

3. In an operating mechanism for effecting the movement of a transformer grounding switch between an open position, a transformer position and a ground position, in combination, a support member for the operating mechanism, a member having a plurality of arcuate longitudinal recesses therein affixed to the support member, an arm member pivotally mounted on the support member, a shaft rotatably carried by the arm member, recess engaging means carried by the shaft disposed for movement longitudinally of the recesses, and a plurality of restraining means dis-

posed in spaced relation along the recesses to correspond to the open, transformer and ground positions of the switch, each of the restraining means comprising a substantially circular enlargement of the longitudinal recesses, the enlargement corresponding to the transformer position being disposed to interconnect the adjacent ends of the plurality of recesses to provide a tortuous path for movement of the recess engaging means along the recesses from the open position, through the transformer position, to the ground position, one of the restraining means cooperating with the recess engaging means to effect a positive stop of the switch at the transformer position during a movement of the switch from the open position to the ground position.

4. In an operating mechanism for effecting the movement of a transformer grounding switch between an open position, a transformer position and a ground position, in combination, a support member for the operating mechanism, a member having an arcuate longitudinal recess therein carried by the support member, an arm member pivotally mounted on the support member, a shaft rotatably carried by the arm member, recess engaging means comprising a segmentally shaped element having a flat lateral surface carried by the shaft disposed for movement longitudinally of the recess, restraining means disposed in spaced relation along the recess corresponding to the open, transformer and ground positions of the switch, and means carried by the shaft disposed for operation to rotate the recess engaging means 180° when the engaging means is in the transformer position whereby the flat surface of the engaging means cooperates with one side of the recess between the open and transformer positions and with the other side of the recess between the transformer and ground positions to control movement of the switch and effect a positive stop thereof in the transformer position during such rotation.

5. In an operating mechanism for effecting the movement of a transformer grounding switch between an open position, a transformer position and a ground position, in combination, a support member for the operating mechanism, an arcuate member having a plurality of arcuate longitudinal recesses therein carried by the support member, an arm member pivotally mounted on the support member, a shaft rotatably carried by the arm member, and recess engaging means carried by the shaft disposed for movement longitudinally of the recesses, the recess engaging means comprising a segmentally shaped element disposed for cooperation with restraining means disposed in spaced relation along the recesses to effect a positive stop of the switch at the transformer position during movement of the switch from the open position to the ground position.

6. In an operating mechanism for effecting the movement of a transformer grounding switch between an open position, a transformer position, and a ground position, in combination, a support member for the operating mechanism, a member having an arcuate longitudinal recess therein carried by the support member, an arm member pivotally mounted on the support member, a shaft rotatably carried by the arm member, recess engaging means comprising a segmentally shaped element having a flat lateral surface carried by the shaft and disposed for movement longitudinally of the recess, restraining means disposed in spaced relation along the recess corresponding to the open, transformer and ground positions of

the switch, means carried by the shaft disposed for operation to rotate the recess engaging means 180° when the engaging means is in the transformer position whereby the flat surface of the engaging means cooperates with one side of the recess between the open and transformer positions and with the other side of the recess between the transformer and ground positions to control movement of the switch and effect a positive stop thereof in the transformer position during such rotation, and means carried by the shaft disposed to cooperate with the arm member when the recess engaging means is in any one of the open, transformer and ground positions for locking the recess engaging means in such position.

7. In an operating mechanism for effecting the movement of a transformer grounding switch between an open position, a transformer position, and a ground position, in combination, a support member for the operating mechanism, a member having an arcuate longitudinal recess therein affixed to the support member, an arm member pivotally mounted on the support member, a shaft rotatably carried by the arm member, recess engaging means carried by the shaft disposed for movement longitudinally of the recess, a plurality of restraining means disposed in spaced relation along the recess to correspond to the open, transformer and ground positions of the switch, one of the restraining means cooperating with the recess engaging means for effecting a positive stop of the switch at the transformer position during a movement of the switch from the open position to the ground position, and means carried by the shaft disposed for imparting a predetermined rotating movement to the engaging means in each of the open, transformer and ground positions.

8. In an operating mechanism for effecting the movement of a transformer grounding switch between an open position, a transformer position and a ground position, in combination, a support member for the operating mechanism, a member having a plurality of arcuate longitudinal recesses therein affixed by the support member, an arm member pivotally mounted on the support member, a shaft rotatably carried by the arm member, recess engaging means carried by the shaft disposed for movement longitudinally of the recesses, a plurality of restraining means disposed in spaced relation along the recesses to correspond to the open, transformer and ground positions of the switch, each of the restraining means comprising a substantially circular enlargement of the longitudinal recesses, the enlargement corresponding to the transformer position being disposed to interconnect the adjacent ends of the plurality of recesses to provide a tortuous path for movement of the recess engaging means along the recesses from the open position, through the transformer position, to the ground position, one of the restraining means cooperating with the recess engaging means to effect a positive stop of the switch at the transformer position during a movement of the switch from the open position to the ground position, and means carried by the shaft disposed to cooperate with the arm member when the recess engaging means is in any one of the open, transformer and ground positions for locking the recess engaging means in such position.

9. In an operating mechanism for effecting the movement of a transformer grounding switch between an open position, a transformer position, and a ground position, in combination, a support member for the operating mechanism, a member having an arcuate longitudinal recess therein affixed to the support member, an arm member pivotally mounted on the support member, a shaft rotatably carried by the arm member, recess engaging means carried by the shaft disposed for movement longitudinally of the recess, a plurality of restraining means disposed in spaced relation along the recess to correspond to the open, transformer and ground positions of the switch, each of the restraining means comprising a substantially circular enlargement of the longitudinal recess, one of the restraining means being disposed to cooperate with the recess engaging means to effect a positive stop of the switch at the transformer position during movement of the switch from the open position to the ground position, and means carried by the shaft disposed to cooperate with the arm member when the recess engaging means is in any one of the open, transformer and ground positions for locking the recess engaging means in such position.

10. In an operating mechanism for effecting the movement of a transformer grounding switch between an open position, a transformer position and a ground position, in combination, a support member for the operating mechanism, a member having an arcuate longitudinal recess therein carried by the support member, an arm member pivotally mounted on the support member, a shaft rotatably carried by the arm member, recess engaging means disposed for movement longitudinally of the recess, the recess engaging means comprising a segmentally shaped element disposed for movement simultaneously with movement of the shaft, a plurality of restraining means disposed in spaced relation along the recess to correspond to the open, transformer and ground positions, one of the restraining means cooperating with the segmentally shaped element for effecting a positive stop of the switch at the transformer position during a movement thereof from the open to the ground position, a plate member carried by the shaft, and locking means disposed to prevent relative movement of the plate member to the arm member when the segmentally shaped element is in any one of the open, transformer and ground positions for locking the segmentally shaped element in such position.
